UNITED STATES PATENT OFFICE.

HARRY W. DAVIS, OF EAST LIVERPOOL, OHIO.

BENCH CLAMP.

Application filed April 16, 1927. Serial No. 184,342.

The object of my said invention is the provision of a simple and efficient bench clamp and one that is capable of being expeditiously and easily operated.

5 To the attainment of the foregoing the invention consists in the improvement hereinafter described and definitely claimed.

In the accompanying drawings, forming part of this specification:—

10 Figure 1 is a top plan view of the bench clamp constituting the preferred embodiment of my invention.

Figure 2 is an end elevation of the clamp.

15 Figure 3 comprises disconnected perspectives of the rectilinearly movable slide member of the clamp and the rubber facing for use at the under side of said slide member.

Similar numerals of reference designate corresponding parts in all of the views of the 20 drawing.

I show in Figures 1 and 2 the body 1 of my novel clamp, the said body 1 being designed to be superposed on a bench or other appropriate support, and also designed to be 25 fastened to the bench or support by nails or screws, not shown, driven through apertures in lugs 2^x. The major portion of the body 1 is formed by a plate 2, and at its under side the plate 2 is provided with a marginal flange 3 from which the lugs 2^x extend and with longitudinal spaced pendent flanges 3^x, the said flanges 3 and 3^x being designed to bear on the surface of the bench so that the plate 2 will be maintained in spaced relation 30 to the said surface. It will also be understood that the body 1 is provided with an up-standing integral flange 4, the said flange 4 being preferably, though not necessarily faced with a strip of wood 5, connected to

35 the flange through the medium of screws 6. Formed in the plate 2 and disposed at right angles to the flange 4 is a slot 7, and in accordance with the preferred embodiment of my invention the plate 2 is provided at

40 its upper side with graduated scales 8, the said scales 8 being arranged at opposite sides of the slot 7 and being designed for use in cooperation with a pointer 9 provided on a slide member 10, so as to enable the user of 45 the clamp to readily ascertain the distance between the face of the flange or jaw 4 and the movable jaw 11 of the clamp.

The movable jaw 11 is superposed upon the body plate 2 and is provided with an 50 abutment 12 at one end, disposed laterally to the major portion of the jaw and it will

also be understood that the jaw 11 is preferably, though not necessarily, provided with a facing 13 of wood or other material designed to prevent bruising of wood or other 60 comparatively soft material interposed and held between the jaw 4 and the jaw 11. At its rear side the jaw 11 is provided with a flange 14 spaced above the plate 2, Figure 2 and it will be understood that the said flange 65 14 is provided with an enlargement 15 in which is a slot 16 extending at an acute angle to the face of the jaw 11.

The slide member 10 of the clamp is disposed above the plate 2 and is provided, by 70 preference, at its under side with a facing 10^x of rubber or other friction creating material, the said facing 10^x being in the form of a strip appropriately attached to the under side of the slide member 10, and the 75 said facing being designed to enable the slide member 10 to take better hold on the upper side of the plate 2 when the wing nut 17 on the headed bolt 18 is tightened. The said headed bolt 18 is extended through the slot 80 7 of the body 1 and also through apertures in the strip 10^x and the slide member 10, and is equipped below the plate 2 with a washer 19, and above the slide member 10 with a washer 20. The slide member 10 is 85 also equipped with a vertical pin 21, the said pin 21 having a portion 21^x below the member 10 and arranged and movable in the slot 7 for the guidance of the slide member 10, and said pin 21 being also provided with 90 a T-head 22 designed to rest above the flange 14 of the jaw 11 with a view to securing the said jaw flange 14 to and on the slide member 10.

It will be apparent from the foregoing 95 that the movable jaw 11 of my novel clamp is capable of simultaneous longitudinal and lateral movement. The piece of material to be clamped is designated by 50 in Figures 1 and 2, and it will be understood that when 100 the said piece of material is moved endwise against the abutment 12 of the jaw 11, the said jaw 11 will be simultaneously moved forward and laterally toward the jaw 4, and in consequence the jaw 11 and the jaw 4 will 105 grip the piece of material throughout the length and height of the jaws and will hold it strongly until released by a rearward movement of the piece of material, the retraction of the piece of material serving by 110 virtue of the frictional contact between the material and the face of the jaw 11 to move

the said jaw 11 rearwardly and laterally away from jaw 4.

It will also be apparent from the foregoing that the slide member 10 and its appurtenances permits of the clamp being changed from right to left hand and vice versa, and the said slide member and its appurtenances also provide for the ready adjustment of the clamp to pieces of material 10 of different sizes. The reversible capacity of the clamp will better be understood when it is stated that the clamp can be changed from right hand to left hand, or from left hand to right hand in a very short time, and 15 in order to make the change it is simply necessary to move the slide member 10 as far as possible from the jaw 4, turn the wing nut 17 so that its wings are longitudinal of the slide member 10, and move the jaw 11 endwise rearwardly and manipulate the same so that its slot 16 is lengthwise of the T-head 22, lift the jaw 11 off the pin 21, turn the jaw 11 upside down, and then replace the jaw 11 on the pin 21. The positioning of the 25 wings of the nut 17 as stated is necessary for the said manipulation of the jaw 11.

In order to assist in the return of the movable jaw to open position and render it easier to place a piece of material in the 30 clamp I provide a retractile spring 60. At one end the said spring is connected to the movable jaw, and at its opposite end the spring is equipped with a pin 61, designed to be removably placed in any one of the 35 lower set of sockets 62, the said set of sockets being employed so that the spring may be tensioned as desired by the operator of the clamp. Manifestly when the clamp is changed for use as a left hand clamp, as 40 before indicated, the pin 61 will be placed in one of the upper sets of sockets 62, Figure 1.

Notwithstanding the capacity of function ascribed to my novel clamp, it will be noted 45 that the clamp is simple and inexpensive in construction, and in general is well adapted to withstand the usage to which bench and analogous clamps are ordinarily subjected.

I have entered into a detailed description 50 of the construction and relative arrangement of the parts embraced in the present and preferred embodiment of my invention in order to impart a full, clear and exact understanding of the said embodiment. I 55 do not desire, however, to be understood as limiting myself to the precise structure illustrated and described, my invention being defined by my appended claims within the scope of which modifications may be made 60 without departure from my invention.

Having thus described the invention, what I claim is:—

1. A clamp comprising a body having a flange constituting a jaw, a slide member 65 guided on the body and movable at right an-

gles to said jaw, and having an upstanding pin, means for adjustably fixing said slide member with respect to said body, and a movable jaw on the body and having a lateral abutment and also having a flange and a slot in said flange and disposed at an acute angle to the face of the movable jaw, said slot receiving the upstanding pin of said slide member.

2. A clamp comprising a body having a plate and pendent flanges at the under side of said plate, the plate being provided with an upstanding flange constituting a jaw and being also provided with a slot disposed at right angles to the face of said jaw, apertured lugs carried by flanges of the plate, a slide member disposed above the plate and having friction creating means at its under side engaging the surface of the plate, a headed bolt having its shank disposed in said slot and extending through an aperture in the slide member, a nut threaded on said bolt shank and disposed above the slide member, a pin carried by the slide member and having a lower portion disposed in the slot and also having an upstanding portion and a T-head thereon, and a movable jaw disposed on the plate and having at its back a flange and also having in said flange a slot disposed at an acute angle to the face of the jaw and receiving the upper portion of the upstanding pin on the slide member, the flange of the movable jaw being disposed under the head of said pin.

3. A clamp comprising a body having a plate and pendent flanges at the under side of said plate, the plate being provided with an upstanding flange constituting a jaw and being also provided with a slot disposed at right angles to the face of said jaw, apertured lugs carried by flanges of the plate, a slide member disposed above the plate and having friction creating means at its under side engaging the surface of the plate, a headed bolt having its shank disposed in said slot and extending through an aperture in the slide member, a nut threaded on said bolt shank and disposed above the slide member, a pin carried by the slide member and having a lower portion disposed in the slot and also having an upstanding portion and a T-head thereon, and a movable jaw disposed on the plate and having at its back a flange and also having in said flange a slot disposed at an acute angle to the face of the jaw and receiving the upper portion of the upstanding pin on the slide member, the flange of the movable jaw being disposed under the head of said pin, the plate being provided at its upper side with a scale, and the slide member being provided with a pointer for cooperation with said scale, and the jaws being faced with comparatively soft material to prevent bruising of material clamped between the jaws.

4. A clamp comprising a body having a flange constituting a jaw, a slide member guided on the body and movable at right angles to said jaw, and having an upstanding pin, means for adjustably fixing said slide member with respect to said body, and a movable jaw on the body and having a lateral abutment and also having a flange and a slot in said flange disposed at an acute angle to the face of the movable jaw, said slot receiving the upstanding pin of said slide member, in combination with a retractile spring interposed between and connected with the body and the movable jaw for assisting in the retraction of the latter.

10 5. A clamp comprising a body having a flange constituting a jaw, a slide member guided on the body and movable at right an-

gles to said jaw, and having an upstanding pin, means for adjustably fixing said slide member with respect to said body, and a movable jaw on the body and having a lateral abutment and also having a flange and a slot in said flange disposed at an acute angle to the face of the movable jaw, said slot receiving the upstanding pin of said slide member, in combination with a retractile spring interposed between and connected with the body and the movable jaw for assisting in the retraction of the latter; the body having a plurality of sockets, and the spring equipped with a pin for removable disposition in one of said sockets.

15 In testimony whereof I affix my signature

HARRY W. DAVIS.
